UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

DISK HARROW.

1,125,514.

Specification of Letters Patent. Patented Jan. 19, 1915.

Application filed May 8, 1914. Serial No. 837,152.

To all whom it may concern:

Be it known that I, WILLIAM S. GRAHAM, a citizen of the United States, and a resident of Canton, in the county of Fulton and State of Illinois, have invented certain new and useful Improvements in Disk Harrows, of which the following is a specification, reference being had to the accompanying drawings.

10 This invention relates to disk harrows of the type employing two separate gangs of disks working side by side and adapted to be angled more or less relative to each other.

It is one of the objects of my invention to 15 provide new and improved means for supporting and controlling scraper blades and for giving them a swinging movement whereby the disks are adapted to be scraped during the operation of the harrow.

20 It is one of my objects to provide improved means for throwing the scrapers out of contact with the cutters and for holding them in such inoperative position but ready for use when desired.

25 It is another object to provide improved means for locking the scrapers in operative scraping position in contact with the peripheries of the cutters.

It is one of the more specific objects of my 30 invention to provide a single lever having two distinct operations, by one of which operations the scraping blades are held out of contact with the disks and by the other of which operations the scraping blades are locked in position to engage the disks at or near their outer peripheries.

It is another object of my invention to 35 improve devices of this type in sundry details hereinafter pointed out.

40 In the drawings, Figure 1 is a plan view of a harrow embodying my improvements, having the driver's seat and the weight-boxes removed; Fig. 2 is a side elevation of my improved machine; Fig. 3 is substan-

45 tially a section taken on lines 3—3 of Fig. 1 but with the weight-boxes in position on the devices; Fig. 4 is a rear elevation of one of the gangs, partly in section, the weight-box being removed; Fig. 5 is an enlarged vertical section through one of the gangs showing the scraper-blades in their normal position adjacent to the centers of the disks; Fig. 6 is a similar view but showing the scraper-blades in position to scrape the outer edges of the disks; Fig. 7 is an enlarged side

elevation, partly in section, of one of the devices for mounting the scraping blades adjustably in operative position; Fig. 8 is an enlarged detail, being a perspective view of the lever for adjusting and locking in 60 position the disk scraper-blades.

Referring to the several figures of the drawings, in which corresponding parts are indicated by the same reference characters, 65 20—21 indicate two parallel bars constituting a short tongue connected at their rear ends to a transverse frame-bar 22 and connected at their forward ends to a bracket 23. The bracket 23 is supported by a truck comprising an axel 24 and wheels 25—26, 70 said truck being connected to said bracket by means of a standard 27. The bracket 23 has connected to its front face a draft-device 28 of any approved type. The bars 20—21 are braced relative to the transverse 75 bar 22 by means of diagonally-positioned bars 29,—said bars being formed integral with each other in the construction shown and in the form of an angle-iron.

30 indicates a seat secured in any suitable 80 manner upon the framework by means of a support 30^a.

Each gang of disks comprises a transverse bar 31 having depending from its under face standards 32—33 carrying at their lower 85 ends bearings 34—35, respectively, in which is mounted a shaft 36 upon which the disks 37 are mounted, said disks being spaced apart upon said shaft by suitable sleeves 38. Each of the cross-bars 31 has secured upon 90 its upper face a weight-box 39 adapted to carry sand, or other suitable material, for increasing the downward pressure upon the disks for causing the device to run at the proper depth. Each of the bearings 34—35 95 is adapted to have oil fed to it by a tube 40 extending downward thereto from an oil-cup 41 mounted in suitable position in the sand-box 39.

Each of the gangs of disks is connected 100 near its outer end to the main frame of the machine by means of two bars 42—43. The bars 43 are pivotally connected at their rear ends to the bearings 35, respectively, and are pivotally connected at their forward ends to the diagonally-positioned brace-bars 29, respectively, by means of bolts 44,—said bars 43 extending through suitable slots 45 in the vertical flange of the main transverse frame-bar 22, as best shown in Fig. 3. The 110

bars 42 are connected at their forward ends to the transverse bars 29, respectively, by the said bolts 44 and extend rearwardly therefrom in position overlying the bars 44, 5 being connected at their rear ends to the transverse bars 31 of the respective gangs.

46—47 indicate levers pivotally mounted upon the short tongue-bars 20—21, respectively, and adapted to be locked in adjusted 10 position relative to circular rack-bars 48—49 carried by said bars. Said levers are connected at their lower ends to the front ends of bars 50—51, respectively, the rear ends of which bars are pivotally connected to the 15 bearings 34 of the respective gangs.

52—53 indicate diagonally-extending brace-bars connected at their rear ends to the bars 31 of the gang frames and connected at their forward ends to the bars 50—51, 20 respectively. As will be readily understood, by a stroke of one of the levers 46—47 upon its release from the rack-bar 48—49, the corresponding gang will be angled through the medium of the bar or link 50—51 relative to 25 the main frame-bar 22, said gangs swinging in such operation upon the bars 42—43.

Coming now to the means for holding the inner ends of the gangs positively in depressed position so that the gangs will have 30 a natural suction tending to draw the disks into the ground and to maintain them in the desired operative position: 54 indicates a transversely-extending rod offset at its ends whereby it is adapted to be swung on the arc 35 of a circle about such offset ends, which are revolvably mounted in brackets 55—56 carried by the main transverse frame-bar 22. Keyed or otherwise fixed upon one end of the rod 54 is a lever 57 which is adapted to 40 be adjusted in the ordinary way relative to a circular rack-bar formed upon said bracket. As will be readily understood, by a stroke of the lever 57 in counter-clockwise direction in Fig. 2, the crank portion of the rod 54 will 45 be swung downward relative to the brackets 55—56. As is best shown in said Fig. 2, the crank portion of said rod directly overlies the bars or links 50—51, whereby a downward movement of such rod causes at the 50 same time a downward movement of the bars or links 50—51 causing a like depression of the inner ends of the gangs. The bar 54 is provided with brackets 58—59 mounted thereon engaging the outer faces 55 of the bars 50—51, serving as means for steadyng the gangs against undue lateral movement.

As will be seen from an inspection of Fig. 2, when the levers 46—47 are given a stroke 60 in clockwise direction in said figure, the lower ends of the levers are moved on the arc of a circle about the axis upon which said levers turn. It would accordingly follow, if no means were used to prevent it, 65 that as one of the levers was moved back

and forth to angle the gangs, the corresponding link 50—51 would be raised or lowered relative to the rod 54 with a corresponding change in the position of the inner end of the gang. In order to prevent such a 70 change in the vertical adjustment of the inner ends of the gangs upon the operation of the levers 47, the links 51 are provided with curved intermediate portions, as clearly shown in Fig. 2, the curvature being such as 75 to offset and equalize the vertical movement of the front ends of the links 50—51. That is to say, as the front end of the link 51 is moved from its uppermost position to its lowermost position, the link 51 would also 80 be shifted longitudinally of itself, bringing the link into such a position that the bar 54 would overlie the uppermost point of curvature. As the lever 47 was then moved in the same direction to the other extreme, the 85 front end of the link 51 would be moved from its lowermost position again to its uppermost position, moving the link 51 longitudinally of itself still farther in the same direction, changing the point of engagement 90 of the bar 54 from the uppermost point of curvature again to the normal.

The scraping devices by which the disks 37 of each gang are kept clean are mounted so as to be operated in unison. For this 95 purpose, each of the transverse bars 31 is provided with two brackets 64—65, in the outer ends of which is revolvably mounted a rock-shaft 66. Upon each of the rock-shafts 66 are fixedly mounted a plurality of brackets 67, each carrying a scraper-blade 68 adapted to be brought into engagement with one of the disks 37, as hereinafter described. Fixed upon the transverse bar 31 of each of the gangs is a bracket 69 100 through the rear end of which the shaft 66 passes. Between the bracket 69 and the next adjacent bracket 67 there is mounted a coiled spring 70 tending to move said bracket 67 together with the rock-shaft 66 105 and parts mounted thereon away from the bracket 69 so as to hold the scrapers 68 normally in contact with the faces of the disks, as will be seen from an inspection of Fig. 4. As is also shown in said figure, one end of 110 the spring 70 engages the transverse bar 31 and the other end engages a lug on the bracket 67 against which the spring bears. The spring is thus adapted to hold the rock-shaft 66 turned normally to the limit of its 115 motion in counter-clockwise direction in Fig. 5 in such position that the scraper-blades 68 are held adjacent to the centers of the disks 37.

One of the scraper-blades 68 of each gang 120 is mounted upon its rock-shaft 66 by means of a device now to be described in lieu of one of the brackets 67. As best shown in Fig. 7, 71—72 indicate two brackets pivotally connected together by means of a bolt 125

or rivet 73 and clamped together upon the opposite side of the rock-shaft 66 by means of a bolt 74, whereby said two brackets are held fixed in position upon the rock-shaft 66. The scraper-blade 68 is secured to the bracket 71 in the same position relative to its disk 37 and relative to the rock-shaft 66 as if it were supported by one of the brackets 67. The bracket 71 has pivotally connected to its forward end a foot-lever 75 which is held adjustably in position relative to said bracket by means of a bolt 76 passing through a slot 77 in the bracket in rear of the pivot upon which said foot-lever is mounted. As will be readily understood, by a downward stroke upon the lever 75 the rock-shaft 66 will be turned in clockwise direction in Figs. 2, 5 and 6, causing all of the scrapers 68 to move in clockwise direction in said figures about the rock-shaft 66, moving the lower ends of the scrapers out of the position shown in Figs. 2 and 5 adjacent to the centers of the disks into or past the position shown in Fig. 6 adjacent to the peripheries of said disks. In order to limit the downward stroke of the lever 75, a set-screw 78 is mounted in the bracket 72 adapted to be brought into contact with the transverse bar 31.

Pivotally mounted upon each of the brackets 72 is a lever 79, mounted thereon by means of a pin or bolt 80. Mounted upon said bolt between its head and the lever 79 is a coiled spring 81 which, by its bearing upon said lever, tends to hold the lever frictionally in position against turning upon said bolt. Mounted upon the bracket 69 is an arm 82 adjacent to the lever 79. As best shown in Fig. 1, the lever 79 is adapted to be turned outward from the position shown at the right-hand side of said figure to the position shown at the left-hand side of said figure, bringing the arm 83 of said lever into bearing upon the arm 82 of the bracket and causing the rock-shaft 66 with the parts carried thereby to move outward against the action of the spring 70, carrying the scrapers 68 out of contact with the disks 37. As shown in this figure, the lever 79 is adapted to be turned in this way into a substantially centered locking position, whereby the scrapers 68 are held out of contact with the disks until the lever is again turned to its normal position, as shown at the right in Fig. 1. The lever 79 has another function in addition to that of holding the scrapers 68 out of contact with the disks as just described. As best shown in Fig. 8, said lever is provided with an arc-shaped cam-flange 84 the faces of which converge toward one end to approximately the thickness of the lever. When the foot-lever 75 has been depressed as shown in Fig. 6, turning the scraper-blades into contact with the peripheries of the disks 37,

the lever 79 can be given a stroke toward the center of the machine, bringing the lever 79 into position overlying the arm 82 and holding the rock-shaft 66 against being returned to normal position by the spring 70. In this position of the lever 79, the flange 84 engages the arm 82, the position at which the scrapers 68 are held in this way relative to the peripheries of the disks being determined by the longitudinal position of the flange 84 relative to the arm 82, which is dependent upon the extent to which the lever 79 is turned on its pivot-pin 80.

By my construction and arrangement, the lever 79 is adapted to be moved into a self-locking position in one direction from the normal for holding the scrapers out of contact with the cutters, or into a variable locking position in the other direction from the normal for holding the scrapers swung against the action of the spring 70 away from the centers of the cutters into variable position opposite the peripheries of the cutters.

What I claim as my invention and desire to secure by Letters Patent, is—

1. In a harrow, the combination of a frame, a gang of revoluble cutters mounted on said frame, scrapers for said revoluble cutters movable laterally of said frame, yielding means tending to hold said scrapers in contact with said cutters, and a lever pivotally mounted relative to said scrapers and movable laterally therewith adapted to be swung laterally into a self-locking position in engagement with the framework for holding the scrapers out of operative contact with said cutters.

2. In a harrow, the combination of a gang of revoluble cutters, a rock-shaft, scrapers for said revoluble cutters adapted to be moved laterally with said rock-shaft, yielding means acting upon said rock-shaft tending to hold said scrapers in contact with said cutters, and a lever movable laterally with said rock-shaft adapted by an operative stroke laterally to move said scrapers out of operative contact with said cutters and adapted to be moved into a substantially-centered locking position for holding said scrapers out of operative contact with said cutters.

3. In a harrow, the combination of a gang of revoluble cutters, a rock-shaft, scrapers for said revoluble cutters adapted to be moved laterally with said rock-shaft, yielding means acting upon said rock-shaft tending to hold said scrapers in contact with said cutters, a lever pivotally mounted on said rock-shaft upon an axis at an angle to said shaft, and means adapted to be engaged by said lever for moving said rock-shaft and said scrapers laterally to carry the scrapers out of operative contact with the cutters.

4. In a harrow, the combination of a gang

- 4
- of revoluble cutters, a rock-shaft, scrapers for said revoluble cutters adapted to be moved laterally with said rock-shaft, yielding means acting upon said rock-shaft tending to hold said scrapers in contact with said cutters, a lever pivotally mounted on said rock-shaft upon an axis at an angle to said shaft, and means adapted to be engaged by said lever for moving said rock-shaft and said scrapers laterally to carry the scrapers out of operative contact with the cutters, said lever being adapted to be moved into a substantially-centered locking position for holding said scrapers out of operative contact with said cutters.
5. In a harrow, the combination of a gang of revoluble cutters, a rock-shaft, scrapers carried by said rock-shaft, yielding means acting upon said rock-shaft tending to hold said scrapers in contact with said cutters, and a lever pivotally mounted upon an axis at an angle to said rock-shaft and movable laterally therewith adapted to move said rock-shaft longitudinally of itself for carrying said scrapers out of contact with said cutters.
6. In a harrow, the combination of a gang of revoluble cutters, a rock-shaft, scrapers carried by said rock-shaft, yielding means acting upon said rock-shaft tending to hold said scrapers in contact with said cutters, a bracket fixedly mounted on said rock-shaft, a lever pivotally mounted on said bracket on an axis at an angle to said shaft, and an arm against which said lever is adapted to bear for forcing said shaft laterally of the machine for carrying said scrapers out of contact with said cutters.
7. In a harrow, the combination of a gang of revoluble cutters, a rock-shaft, scrapers carried by said rock-shaft, yielding means acting upon said rock-shaft tending to hold said scrapers in contact with said cutters, a lever adapted to act upon said rock-shaft to move said scrapers out of contact with said cutters, and means for holding said lever against turning relative to said shaft as said shaft is rocked.
8. In a harrow, the combination of a gang of revoluble cutters, a rock-shaft, scrapers carried by said rock-shaft, yielding means acting upon said rock-shaft tending to hold said scrapers in contact with said cutters, a lever adapted to act upon said rock-shaft to move said scrapers out of contact with said cutters, and frictional means for holding said lever against turning relative to said shaft as said shaft is rocked.
9. In a harrow, the combination of a gang of revoluble cutters, a rock-shaft, scrapers carried by said rock-shaft, yielding means acting upon said rock-shaft tending to hold said scrapers in contact with said cutters, a lever adapted to act upon said rock-shaft to move said scrapers out of contact with said

cutters, and a spring adapted to frictionally engage said lever for holding it against turning relative to said shaft as said shaft is rocked.

10. In a harrow, the combination of a frame, a gang of cutters revolvably mounted thereon, a rock-shaft revolvably mounted on said frame, scrapers carried by said rock-shaft, yielding means acting upon said rock-shaft tending to hold said scrapers in contact with said cutters, an arm extending from said frame, a bracket fixedly mounted on said rock-shaft adjacent to said arm, and a lever pivotally mounted on said bracket adapted to be turned into engagement with said arm for forcing said rock-shaft longitudinally of itself against the action of said yielding means for carrying said scrapers out of contact with said cutters.

11. In a harrow, the combination of a frame, a gang of cutters revolvably mounted thereon, a rock-shaft revolvably mounted on said frame, scrapers carried by said rock-shaft, yielding means acting upon said rock-shaft tending to hold said scrapers in contact with said cutters, an arm extending from said frame, a bracket fixedly mounted on said rock-shaft adjacent to said arm, and a lever pivotally mounted on said bracket adapted to be turned into engagement with said arm for forcing said rock-shaft longitudinally of itself against the action of said yielding means for carrying said scrapers out of contact with said cutters, said lever being adapted to be turned into a substantially centered locking position for holding said scrapers out of operative contact with said cutters.

12. In a harrow, the combination of a gang of revoluble cutters, a rock-shaft, scrapers movable with said rock-shaft, yielding means tending to hold said rock-shaft turned in position with the scrapers adjacent to the centers of said cutters, a lever mounted on said shaft and having a stroke longitudinally thereof and means for rocking said shaft for carrying said scrapers into contact with the peripheries of the cutters, said lever upon the rocking of said shaft being adapted to be given an operative stroke whereby the shaft is held in turned position independently of the rocking means against the action of said yielding means.

13. In a harrow, the combination of a gang of revoluble cutters, a rock-shaft, scrapers movable with said rock-shaft, yielding means tending to hold said rock-shaft turned in normal position with the scrapers adjacent to the centers of the cutters, means for rocking said shaft for carrying the scrapers into contact with the peripheries of the cutters, a lever having a stroke longitudinally of said shaft, and an arm normally out of position for engagement by said lever adapted to be engaged by said lever

when the shaft has been rocked to carry the scrapers to the peripheries of the cutters whereby the shaft and scrapers are held against returning to normal position.

- 5 14. In a harrow, the combination of a gang of revoluble cutters, a rock-shaft, scrapers movable with said rock-shaft, yielding means tending to hold said rock-shaft turned in normal position with the 60
10 scrapers adjacent to the centers of the cutters, a lever having a stroke longitudinally of said shaft, an arm adapted to be engaged by said lever as desired for holding the shaft against returning to normal position when
15 the shaft has been turned for carrying the scrapers into contact with the peripheries of the cutters, and frictional means for holding said lever against turning relative to said shaft as said shaft is rocked.
- 20 15. In a harrow, the combination of a gang of revoluble cutters, a rock-shaft, scrapers movable with said rock-shaft, yielding means tending to hold said rock-shaft turned in position with the scrapers 65
25 adjacent to the centers of said cutters, a lever having a stroke longitudinally of said shaft, and means for rocking said shaft for carrying said scrapers into contact with the peripheries of the cutters, said lever upon 70
30 the rocking of said shaft being adapted to be given a variable operative stroke whereby the shaft is held in variable turned position 75
against the action of said yielding means.
16. In a harrow, the combination of a 35 gang of revoluble cutters, a rock-shaft, scrapers movable with said rock-shaft, yielding means tending to hold said rock-shaft turned in normal position with the scrapers adjacent to the centers of the cutters, a lever having a cam thereon adapted 80
40 to have a stroke longitudinally of said shaft, and an arm adapted to be engaged by said cam for holding the shaft against returning to normal position when the shaft has 85
45 been turned for carrying the scrapers into contact with the peripheries of the cutters.
17. In a harrow, the combination of a gang of revoluble cutters, a rock-shaft, scrapers movable with said rock-shaft, yielding means tending to hold said rock-shaft turned in normal position with the scrapers adjacent to the centers of the cutters, a lever having a stroke longitudinally of said shaft, said lever comprising a cam 90
50 flange arranged on an arc about its pivotal point, and an arm adapted to be engaged by 95
55
- said cam flange upon a stroke of said lever to hold said shaft in variable turned position when the shaft has been rocked to carry the scrapers into contact with the peripheries of the cutters. 60
18. In a harrow, the combination of a gang of revoluble cutters, a rock-shaft, scrapers movable with said rock-shaft, yielding means tending to hold said rock-shaft turned in position with the scrapers adjacent to the centers of said cutters, a lever pivotally mounted on said shaft adapted to swing longitudinally thereof and adapted when said shaft is turned carrying 70
said scrapers into contact with the peripheries of the cutters to be swung to hold the shaft in turned position against the action of said yielding means.
19. In a harrow, the combination of a gang of revoluble cutters, scrapers for said revoluble cutters, yielding means tending to hold said scrapers in contact with said cutters adjacent to their centers, and a lever by a stroke of which in one direction said 80
scrapers are adapted to be moved out of contact with said cutters and by a stroke of which in the other direction when said scrapers have been moved into contact with the peripheries of said cutters the scrapers 85
are adapted to be held in such position against the action of said yielding means.
20. In a harrow, the combination of a gang of revoluble cutters, a rock-shaft, scrapers carried by said rock-shaft, yielding 90
means tending to hold said rock-shaft turned in normal position with the scrapers substantially opposite the centers of the cutters and in contact therewith, a lever carried by said rock-shaft, and an arm mounted adjacent to said lever, said lever being 95
adapted by a stroke in one direction to be brought into engagement with said arm for forcing said rock-shaft longitudinally of itself against the action of said yielding 100
means and adapted by a stroke in the opposite direction when said rock-shaft has been turned to bring the scrapers into contact with the peripheries of the cutters to engage said arm to lock the scrapers against 105
returning to position opposite the centers of the cutters.
